UNITED STATES PATENT OFFICE.

EMILE MAERTENS, OF PROVIDENCE, RHODE ISLAND.

PROCESS OF AND APPARATUS FOR TREATING TEXTILE FIBERS.

SPECIFICATION forming part of Letters Patent No. 509,351, dated November 21, 1893.

Application filed January 27, 1892. Serial No. 419,439. (No model.)

To all whom it may concern:

Be it known that I, EMILE MAERTENS, a citizen of the United States, residing at Providence, in the county of Providence and State 5 of Rhode Island, have invented certain new and useful Improvements in Processes of and Apparatus for Treating Textile Fibers; and I do hereby declare the following to be a full, clear, and exact description of the invention, 10 such as will enable others skilled in the art to which it appertains to make and use the same, reference being had to the accompanying drawings, and to letters or figures of reference marked thereon, which form a part of 15 this specification.

In the mechanical treatment of textile fibers during the past few years, but more particularly such operations or processes as have special reference to bleaching or dyeing sliver, roving, and yarn, the results have generally indicated to the operator or experimenter the desirability of so arranging the several operations that they may be easily and quickly effected, thereby not only materially increasing the output during a given 20 length of time but at the same time being less wasteful of the treating agents; moreover, the cost of labor incident to such operations may be also reduced if the apparatus be made 25 sufficiently compact and accessible. From this it can be safely asserted that the product would be more evenly treated and present a smoother appearance because it receives less handling.

30 My present invention relates to apparatus or machinery of the class just referred to, that is apparatus adapted to chemically treat textile fibers in any form, as for example, sliver, roving and yarn, or even the raw material or cloth, when placed in or wound upon perforated or porous holders. After being thus mounted the chemical or treating agents, in a liquid form, are passed through the mass of material mounted upon the holder.

35 I would state, as indicated in the preceding paragraph, that I am aware that textile materials mounted upon perforated holders have been treated with liquids in both open and closed kairs, and that such liquids have been 40 circulated through the materials; also that a minus as well as a plus pressure has been employed in mechanisms of this character, and

further that means has been provided for returning the treating liquids to the storage tanks.

The object I have in view is to provide an apparatus with means whereby textile fibers in various forms may be scoured, bleached, dyed, dried, or otherwise treated in large or small quantities without waste of dye stuffs or other 55 treating materials. To this end my invention consists, essentially, of apparatus or machinery for treating fibrous materials mounted upon perforated or porous holders, the parts of said apparatus being constructed, arranged and operated, all as more fully hereinafter set forth and claimed.

Some of the characteristic features possessed by my improved apparatus are as follows, viz: It is comparatively simple in its 70 construction and manner of operation; its capacity for treating fibrous material is very great as compared with the space occupied; the materials thus operated upon are treated with thoroughness and uniformity; samples 75 of the material being operated upon may be readily exposed and inspected without interrupting the general operation; the facility for using treating liquids of any desired degree of solution, and either cold, warm or boiling; 80 its provision for increasing and diminishing the temperature of the liquid at will; the absence of steam or vapor and surface water usually heretofore inherent in dye houses; the treatment of the materials without rehandling 85 while the latter are being subjected to either scouring, bleaching, mordanting, dyeing or other liquids, either oxidizable or non-oxidizable; the readiness with which a circulation of either cold or warm air may be substituted for the liquids for oxidizing or drying purposes, and the comparatively small amount of manual labor required in the treatment of a large volume of material or output.

In order to clearly set forth my improvements I have prepared the accompanying fourteen sheets of drawings, which not only represent the apparatus complete as in use, together with a modification of the same, but also the several parts more in detail, that is 95 to say—

Figure 1, Sheet 1, is a front elevation showing the complete apparatus in a duplex form. Fig. 2, Sheet 2, is a side elevation, taken

through the line $\alpha\alpha$ of Fig. 1. Fig. 3, Sheet 3, is a plan view of the same, showing also a manner of arranging the overhead piping. Fig. 4, Sheet 4, is a plan view, showing the arrangement of the bottom piping underneath the keirs, &c. Fig. 5, Sheet 5, is a plan view in reduced scale, showing the general arrangement of the apparatus, combined with the series of tanks or reservoirs from which the keirs are supplied. Fig. 6, Sheet 6, is a vertical sectional view, enlarged, taken through the center of a keir. Fig. 7, is a horizontal sectional view of the keir, taken on line $\alpha\alpha$ of Fig. 6. Fig. 8 is a plan view of the keir heads. Fig. 9 is an enlarged vertical sectional view, taken on line $m m$ of Fig. 6, showing the discharge valve. Fig. 10, Sheet 7, is a front elevation of the four-way valve, or valve and chamber from which the liquids are automatically and intermittently distributed. Fig. 11 is a longitudinal sectional view, taken on line $a a$ of Fig. 10. Fig. 12 is a transverse sectional view, taken on line $\alpha\alpha$ of Fig. 11. Fig. 13 is a partial front sectional view, taken on line $o o$ of Fig. 11. Fig. 14, Sheet 8, is a side elevation, in partial section, showing the heater complete. Fig. 15 is an inverted horizontal sectional view, taken on line $\alpha\alpha$ of Fig. 14. Fig. 16 is a plan view of the heater. Figs. 17, 18 and 19, Sheet 9, are longitudinal sectional views of the perforated spools or holders adapted to receive and retain the fibrous material while the latter is being subjected to the several treating operations. Fig. 20 is an enlarged view showing an arrangement of the perforations formed in the spool's barrel. Fig. 21 is an enlarged vertical central sectional view, taken through the lower end of the spool, showing the manner of mounting it in sockets screwed into the bottom of the keir. Fig. 22 is a plan view of the socket. Fig. 23, Sheet 10, is a partial sectional view of the keir, showing the testing or sampling valve mounted therein, as in use. Fig. 24 is a side elevation of the testing valve, enlarged. Fig. 25 is a central longitudinal sectional view thereof. Fig. 26 is a side view, showing the parts in the working position, the sleeve being dropped. Fig. 27 is a side view, in reduced scale, showing the filled main spool provided with a supplemental small spool or bobbin at the top from which the material to be sampled is taken. Fig. 28 is an enlarged side view of the supplemental spool and load wound thereon. Fig. 29, Sheet 11, is a central sectional view of the dye-liquor tank, die-filter, pump, &c., connected by piping, as in use. Fig. 30 is a partial plan view of the spider adapted to be located in the bottom of the tank. Fig. 31 is an enlarged sectional view, taken through the bottom portion of the dye-liquor tank. Fig. 32, Sheet 12, is a side elevation representing a modification of my apparatus which in some cases can be as readily employed for the treatment of fibrous materials. The keirs may be used open or closed. Fig. 33 is a partial front elevation

showing some of the piping therefor. Fig. 34, Sheet 13, is a plan view of the apparatus shown in Fig. 32. Fig. 35 is a plan view of the inlet piping, and Fig. 36, Sheet 14, is a vertical sectional view, in partial elevation, taken on line $\alpha\alpha$ of Fig. 34.

In the following description I shall so far as possible describe the details of the apparatus represented in the numerical order of the drawings. It is assumed that the functions of an engine, pump, valves, blower, heater and tanks are in general well understood. Therefore I do not deem it necessary in this specification to particularly describe their manner of operation, except where an arrangement of the parts produces results which differ in some respects from the usual practice. I would further state that my improved apparatus may be adapted to one keir only, but such an arrangement is in general not so desirable as a system involving the employment of two or more keirs, because in the latter case the relative cost of the machinery, the space occupied by it and the time required to complete the treatment of the materials is less than that where one keir is in use. In the drawings I have represented a duplex system, or rather a system in which two treating keirs are used.

The first five sheets of drawings represent my improved system and apparatus as a whole when in use.

The two vertical main keirs 1 arranged as shown in the drawings are adapted to receive the fibrous materials to be treated through doors 2 formed in the walls of the keirs. The keirs are in communication with the rotary or centrifugal pump 7 both at their top and bottom inlets through the medium of the four-way valve or automatic distributor (hereinafter more fully described) placed above the pump's outlet. The upper main branch piping 10 and its connections lead from said distributor to the top outlets of the keirs, and the lower main branch piping 9 and its connections lead from the distributor to the bottom outlets of the keirs. The top piping 23 serves to connect the distributor with the heater or reservoir 8, the latter being in one sense a continuation of the pipe 23 and discharges into the lower pipes 24 and 21 via the valve 24^a. The discharge from the pump 7 enters the distributor through the cross 22 and valve 22^a. The suction end 21^a of the pump connects with one of the main lower pipes 21 and the pump is operated by a motor or engine 26. The pump is provided with a relief valve 20 located in the discharge connections. The overflow or surcharge passes through said valve (when it opens) downwardly into the pipe 19 back to the main 21.

Referring to Figs. 4 and 5, a manifold 27 is connected by stop-valves with a series of supply pipes leading from the cold-water, hot-water, mordant and logwood tanks, c , h , m and l , respectively. The discharge from the pump may be conducted to the several tanks

by opening the valve 25^b, the liquid then passing through pipe 25 into the manifold from whence it flows to the desired tank by simply opening the corresponding valve. The bottom outlets of the keirs communicate with the sewer by means of the pipes 13, 11, and the interposed valves 11^a. Said outlets also communicate with the reservoir or indigo-tank *i* by means of piping 13, 12, and stop-valves 12^a, and *i'*. These keirs may discharge into the main 24 communicating with the heater, &c., by means of the piping 9 and valves 9^a and 24^c. The top inlets of the keirs communicate with the pressure blower 28 through piping 14, 14^c, air-chambers or headers 14^b and valves 14^a. The air-chambers are in communication with an ejector *e* (Fig. 1) by means of the piping 15, 15^b, and valves 15^a, 15^c. By opening the lower valve 15^d, the valves 15^a, 15^c, being also open, the keirs may be exhausted without passing through the ejector.

30, Fig. 3, indicates the dye-tank, and 29 the pump for discharging the concentrated 25 treating liquid into the heater 8 through pipe 29^a and valve 29^b.

The valved pipe 21^c drains the main 21 and all piping below the T's 13 into the sewer. The valved pipe 27^a drains the manifold into 30 the sewer.

The two main keirs 1 are provided each with a thermometer 4 for indicating the temperature of the interior of the keir; a water-glass gage 3 to show the height of liquid in 35 the keir; a pressure gage 5^a communicating with the lower chamber of the keir; a similar gage 5^c communicating with the upper chamber, and a vacuum gage 5^b also connected with said upper chamber. The keirs 40 are further provided with a testing-valve 31 and a relief-valve 18^a discharging into heater 8 via pipe 18.

The cross 22 (Fig. 1) carries a gage *p* for indicating the pressure under which the pump 45 7 delivers the liquor. It also carries an air-chamber 22^c.

The heater 8 is provided with a water-glass 8^c; a valved pipe 8^a for admitting steam to the coils, and a similar pipe 8^b for letting water into the coils when desired. It is further provided with an air inlet at 8^c and an outlet to the atmosphere at 8^d. At the bottom a pipe 8^e leads the exhaust or drip from the coils to the sewer. The lower valved connection 29^b admits concentrated treating liquor from the pipe 29^a, and a similar connection 8^a admits live steam.

Referring now more particularly to the construction of the keirs 1, as represented on 60 Sheet 6 of the drawings, it will be seen that 6 indicates the stiffened upper head and 6^a the lower head of cast metal; the shell itself being of wrought metal riveted to the heads. The keir is provided with legs 6^b resting upon 65 the floor. The upper head has a main central opening 6^c communicating with the main piping 10, and 14, and also with a series of

pipes 6^d radiating therefrom and cast into the head; each pipe opening into the keir-chamber by means of the series of small 70 holes 6^e. These pipes and holes are arranged in this manner in order to insure a more uniform distribution of the liquid charges over the entire surface of the keir. The lower head 6^a is also provided, like the upper one, 75 with a central opening and apertured radiating pipes. The lower head has, however, in addition a chamber 6^f communicating directly with the several outlets 6^f, as clearly shown in Fig. 6. The upper face or wall 6^g 80 of the bottom head is perforated with a series of holes 6^h into which are fixed a corresponding number of sockets 32 (Fig. 21) arranged to receive the spools or holders 33. The communication between the chamber 6^g 85 and the interior of the keir when in use is through the holders mounted in said sockets. The bottom head is provided with a valve 34 for quickly emptying the keir when desired; the valve being operated by the hand-wheel 90 34^a secured to the lower end of the valve-stem 34^b, as clearly shown in Fig. 9. The two heads of the keir are connected by the strong central bolt or stay *b*. In keirs of large size I prefer to provide them with two doors 2, oppositely located. It is through these doors 95 that the keir is loaded and unloaded. It will be noticed that a sampling-valve 31 is mounted in the upper head of the keir. One or more of these valves may be used; a more detailed description thereof being hereinafter found.

In Sheet 7 of the drawings I have represented an automatic distributor 35, or four-way valve, adapted in use, after the keirs are 105 filled with the treating liquid, to turn the latter through the materials in opposite directions intermittently and alternately; that is the action of the pump 7 through the automatic distributor causes a circulation in one 110 direction by forcing the liquid through the materials for a certain period of time; the position of the valve is then automatically changed, thereby reversing the circulation, the result being to force the liquid in the opposite direction through the materials a corresponding length of time; the operation being thus continued as long as desired or necessary to complete the treatment. The distributor is provided with a chamber 35^a having four nozzles *n*, *n'*, *n*², *n*³, communicating therewith arranged in the form of a cross. See Fig. 12. The nozzle *n*³ is connected with the discharge pipe leading from the pump. The nozzle *n* connects with the heater 8, the latter 115 being in direct connection with the suction side of the pump. As drawn the nozzle *n'* connects with the bottoms of the keirs, and the nozzle *n*² with the tops. Within the valve chamber 35^a is fitted the valve proper or movable wing 36 which divides the chamber longitudinally. The valve is secured to the shaft or stem 36^a. The front and back heads or covers, 37, 37^a, respectively, are bored out and 120 125 130

serve as bearings for the valve and stem. The front head is provided with a hub on which the worm-wheel or disk 38 is loosely mounted. A common stuffing-box 39 is employed to prevent leakage around the valve-stem. The disk is provided with a peripheral notch 38^b adjacent to which is secured a toothed segment 38^a. At one side, the left, of the disk is mounted in the frame 40^a, a pinion 40, a cam 39^b and crank-disk 39, the three parts last named being loosely mounted upon the stud 39^a. A connection 39^d is jointed to the crank-disk and to the valve-arm 39^c. By means of a continuously revolving sprocket-wheel w^3 and worm w' secured to the shaft w^2 the loosely mounted disk 38 is revolved correspondingly; the latter being timed to make one turn, say, in two minutes. The segment 38^a and pinion 40 are so proportioned and arranged that the latter is revolved one-half turn per revolution of 38 by the engagement of the teeth, such movement of the pinion causing the valve 36 to change its position, (see full-line and dotted-line positions Fig. 12) the change being effected in about seven seconds. While such change is being made, the end of the cam 39^b revolves freely in the notch 38^a, as in Fig. 13, but immediately thereafter the continued movement of the parts causes the adjacent concave side 39^c of the cam to engage the disk's periphery, thereby as it were locking the valve in position until the next change is effected; Fig. 10 shows the relation of the parts when thus locked. In these several figures the valve for the time being is represented as distributing or circulating the treating liquid (as it comes upwardly through the valve 22^a from the pump 7) into the bottoms of the keirs from whence it passes under pressure upwardly through the perforated holders and the material or load mounted thereon and thence out at the tops of the keirs; the liquid upon issuing from the latter passes to the distributing valve-chamber 35^a via the pipes 14, 10, 10^b, whence it is diverted into the top of the heater 8 via pipe 23, thence downwardly through the heater and valve 24^a into pipes 24, and 21, and from the latter upwardly into the suction side 21^a of the pump, thus completing the circuit in one direction. When the valve 36 stands in the dotted-line position (Fig. 12) the circulation is reversed, that is the liquid then enters the tops of the keirs and passes out at the bottoms, meanwhile passing through the materials and perforated holders. In both cases the liquid first enters the distributor through the valve 22^a connected with the delivery side of the pump, the discharge from the keirs being always into the pipe 23, or top of heater. I would state that the pointer x , Fig. 10, indicates to the operator the direction of the circulation; that is when pointing downwardly it shows that the liquid is passing into the bottoms of the keirs, and when in the upper position it indicates that the flow is into the tops. The wing or valve

36 is made narrow, (its thickness being less than the diameter of the passages across which it moves) because for a short time after it leaves its seat in moving to the other position the four nozzles are in communication with each other, thus allowing the several differently flowing currents to neutralize each other gradually preparatory to changing their direction and thus avoid the shock or strain, such as would be due to a more rapid reversal resulting in the meeting of large bodies of liquors moving swiftly in different directions.

The heater 8 before referred to is located in the circulation in such manner between the pump and keirs that it also serves as an auxiliary reservoir wherein the treating liquor may be either heated, cooled, oxidized or diluted with dye-stuffs or other treating agents according to the requirements of the materials being acted upon within the keirs. The heater is represented more in detail in Figs. 14, 15, and 16, wherein the vertical shell 90 is riveted to the upper and lower heads. The heater chamber is partly filled with a series of pipe coils 41, each being connected with the top and bottom headers 41^a. Steam and water pipes 8^a, 8^b, unite in a T 41^b at the top and extend downwardly therefrom into the upper header; the exhaust or waste from the coils passes into the bottom header and from thence into the pipe 8^c. When in use the treating liquor enters at the top of the heater through pipe 23 and after circulating around the exterior of the coils returns to the pump through the bottom valve 24^a, &c., as before stated. The valved pipe 8^a admits exhaust steam to the coils for heating purposes, and the pipe 8^b is employed to admit water for cooling purposes. The valved pipe 8^c serves to conduct air from a blower to the heater for oxidizing purposes, and the pipe 8^d is used for the escape of air and gases from the heater. 8^e indicates a safety or relief valve. The valve or pipe 29^b introduces concentrated treating-liquor at the bottom which is diluted with the liquor in the heater, and the pipe 8^h serves to admit live steam into the heater when desired, as for example when exhaust steam is not available or sufficient in pressure. The pipe 18 is for conducting the waste liquor or overflow from the keirs into the heater whenever the relief valves 18^a open. I would add that in practice I usually prefer the average level of the liquor within the heater to stand about on the dotted line o , Fig. 14, thus leaving an air space at the top which acts as a cushion and in a measure relieve the piping system from excessive stains; although in some cases when the presence of air would be injurious the air space is omitted and the entire system filled with the treating-liquid.

Into the holes 6^h formed in the bottom of the keirs are screwed sockets 32 arranged in turn to receive the lower open ends b^3 (Figs. 17 to 21) of the perforated holders 33.

These holders consist each of a central laterally perforated tube d , the upper and lower heads 33^b , 33^c , and the perforated shell or cylinder 33^a fitting into the adjacent faces 5 of said heads. The tube d is, as drawn, screwed into the lower head and extends through the upper head, being surmounted by a cap-nut d^2 , thereby firmly clamping the several parts together. It will be observed, 10 referring more particularly to Figs. 21, 22, that the head 33^c of the holder is provided with a downwardly extending loop or eye b^2 adapted to receive an end of the curved pin b' forming a part of the socket-piece 32. By 15 this device the holder is detachably secured to the bottom of the keir upon turning the holder axially in either direction until it receives the corresponding end of the pin b' . I prefer to make the barred portions 33^a of 20 the holders of sheet-metal tubes, the holes or perforations being subsequently punched therein. Fig. 20 shows a portion of the tube's surface provided with holes. I also preferably make said holders or perforated spools, 25 comparatively large, or long, so as to carry say some six to ten pounds of fibrous materials when loosely wound or wrapped thinly thereon; the broken line m^2 , Fig. 17, indicates the outline of a filled holder.

30 In some cases it may be desirable to use shorter spools, in which event they may be constructed and arranged as shown in Fig. 19, wherein three holders 33 are mounted upon the laterally perforated central tube d ; 35 the cap-nut d^2 serving to firmly retain them in place thereon. A loose collar d^3 is interposed between the ends of adjacent holders, all as clearly shown. In Fig. 18 the top head 33^b is represented as having the end of the 40 tube d screwed into it; the head being provided with a projecting screw-threaded central outlet d^4 sealed by the cap-nut d^2 . This arrangement, however, is more particularly adapted to receive a test-spool about to be 45 described, and illustrated by the next succeeding sheet of drawings.

The sampling or testing-valve 31 screwed into the top head of the keir is represented in detail in Figs. 23 to 26. It consists essentially of a head or body portion 31^a composed of two parts screwed together, and the vertically guided piston f^3 backed by a spring s . The lower portion of said body is provided with a central hole f^5 adapted in use to communicate with the interior of the keir. The upper end of the hole is reduced in diameter but being of sufficient size for the passage of an end of the material t being treated. The lower end of the piston is faced with rubber 55 f^4 or other suitable elastic substance, thus forming what may be considered a valve for closing the outlet f^5 . A sleeve f^2 is fitted to slide up and down over the upper portion of the head; a stop s' serves to prevent the sleeve from being accidentally removed. This 60 sleeve when in use is dropped, as shown in Figs. 23 and 26, thereby preventing the liq-

uid from flying upward from the keir when the valve is open.

By means of the arrangement just described 70 samples of the material t being treated may be taken from the keir at any time without interrupting the main operation. When yarn is to be dyed or treated on holders 33 the end of the thread may be first taken from one of 75 them and run upwardly through the sampling valve and guide g^2 , as shown in Fig. 23. Now, when a sample is to be taken the operator first lifts the valve by means of the supported cord f , followed by the drawing out a 80 sufficient length of the yarn t ; the valve automatically returning to its seat upon releasing the cord. The testing may be repeated from time to time as desired. In order to 85 protect the thread and also to prevent it from being drawn into the openings 6^1 formed in the keir's upper head I employ a circular open-ended hood g , the same being secured to and extending downwardly from the under side of said keir-head, and also inclosing the 90 upper portion of the holder 33, as in Fig. 23.

When slubbing or a thick sliver is to be treated, instead of running the same through the sampling-valve I take some yarn t made from the same quality of stock or material 95 and wind it upon a small perforated holder 33^d , its lower end being open and adapted to be secured onto the upper end, d^4 , Fig. 18, of the main holder 33, see Figs. 27 and 28. When thus arranged the circulation through 100 the main and supplemental holders is the same in each. Therefore the treated yarn when sampled will indicate correspondingly the appearance of the slubbing or sliver wound on the main holder when it is spun 105 into yarn.

By the employment of the double guide or flier g^1 , the hood g may be dispensed with, as it imparts enough tension to the yarn to prevent it from being drawn into the keir- 110 head openings.

Fig. 29, Sheet 11 of the drawings, represents a vertical central sectional view of the apparatus which I employ for holding, dissolving, and filtering or straining concentrated dye-stuff or other treating materials preparatory to being injected therefrom into the main circulation. 115 30, indicates the dye-tank and 50 the filtering strainer located beneath the tank. The tank 30 is supported by legs 43 120 and is, or may be, open at the top and provided with a depressed or concave head 42 at the bottom; the latter having a circular grid or spider 44 fitted therein on top of which is secured by a ring 45^a a perforated 125 disk or strainer 45. See also Fig. 31. Between the strainer and the adjacent lower portion of the head is formed a settling chamber 42^a, the outlet therefrom being through the center pipe 46 communicating right and 130 left with the pipe 46^a; the latter by means of the valve 46^c communicating with the upper portion or space 51^a of the filter 50, and also by the valve 46^b with the suction side of the

force pump 29, which discharges into the heater *via* pipe 29^a and valve 29^b, before described. The pipe *k* admits steam into the tank, the pipe *k'* water and the pipe *k²* liquor forced by the main pump 7. The filtering strainer 50 has a concave head 52 at the bottom from the center of which the outlet 54^a connects with the horizontal pipe 47; the latter also connecting with the pipe 46^a communicating with the pump 29. At the bottom of the filter is located a strainer 55 on which rest the filtering materials 50^a, as for example, gravel, crushed quartz, &c.; the strainer itself being supported by a spider 53, thus forming below the strainer a chamber 54 from which the filtered dye-liquor is distributed as desired.

In the operation of the apparatus represented by Fig. 29 the treating material is introduced into the tank 30, when if necessary it is further diluted with water or other liquid, and boiled or not; the graduated measuring gage 30^a indicating at the time the amount of undiluted or diluted concentrated liquor or treating material thus introduced. When the treating material is ready to be injected into the main connections valve 46^c is opened thus admitting it from the tank into the chamber 51^a of the filter; the liquor percolates downwardly through the material 50^a into the pump 29, *via* the piping 54^a and 47, the valve 47^a being open, and valve 46^b closed; the action of the pump now forces it therefrom into the heater and main circulation. The tank strainer 45 prevents all chips, impurities or foreign matter, as well as any undissolved material, larger than the mesh or holes, from passing through into the filter; but it does not always retain within the tank undissolved dye-stuffs introduced in the form of thick paste, or even powder, as such materials will sometimes "cake" or "lump-up" and form specks. Now, if such specks should enter the main circulation they would cause uneven work because they, as a rule, fasten themselves to the material under treatment. Consequently the liquid cannot act upon the material uniformly at such places or spots. I overcome the objection just referred to by means of the bed 50^a of filtering substances, because the latter collects and retains said impurities, &c., until they are dissolved or thrown off by a subsequent washing. When all the liquor has been exhausted from the tank 30 it is washed out by opening valve *k²* which admits liquor from the main circulation and a stream of it is left running until it is assumed that all the soluble material held by the filter and strainer has been absorbed by the current thus induced and carried by it into the main circulation. If it should be necessary to add more concentrated or primary treating material to the treating liquid it is diluted by a supply from valve *k²* thus making it unnecessary to employ additional liquor for dilution beyond that already in use in the circulation. The liquor may run di-

rectly from the tank to the pump 29, thus cutting out the filter, by closing valves 46^c and 47^a and opening valve 46^b. When sufficient treating material has been introduced into the main circulation the pump is stopped and all valves leading thereto closed. The tank is washed out and drained into sewer 48^a by opening valve 46^d; valves 48^b and 49^a being closed. The filtering strainer 50 is cleaned by opening valve 48^b (46^d and 49^a being closed) leading to sewer connection 48^a, and passing a current of water under pressure upwardly through the filter bed 50^a; water for the purpose being admitted through valve 47^b, thereby causing all the impurities and foreign matter to rise and float off through said valve 48^b into the sewer. At the same time by opening the valve 49^a connected with the cross 48 and escape pipe 85 49 the operator can judge from the appearance of the waste wash water passing from the pipe 49 whether the filter has been sufficiently cleaned.

A pressure gage 56 is connected with the top and bottom portions of the filter 50, said connection being provided with cocks *e'*, *e²*. By means of this gage the operator is able to determine whether the flow of liquor is regular, &c.—that is the varying pressures (if any) indicated on the dial denote to the attendant, after opening and closing the corresponding cocks, whether the bed 50^a is clogged or whether the passage of the washing liquor out of the filter is free and unobstructed. It is evident that the piping can be arranged so as to let the liquor from the tank 30 run through the pump first and be forced by the latter through the filter 50 into the main circulation by simply connecting the pump's outlet with the filter inlet controlled by valve 46^c, at the same time connecting the bottom outlet 54^a to the main circulation by a valved pipe leading therefrom to the heater.

The following is a description of the operation of the complete apparatus, and for the sake of illustration it is assumed that the fibrous material to be treated is to be scoured, mordanted and dyed—that is to say, the series of perforated holders 33 after being filled and passed through the doors 2 into the keirs 1, 1, are placed vertically in the sockets 32, at the same time locking them in place by means of the pins *b'*. Upon closing the doors I next open the two valves 9^a and 24^c thus putting the mains 24 and 21 in communication with the bottoms of the keirs, followed by opening the two small valves 15^a and 15^c (Fig. 1) and start the ejector *e*, thus producing a partial vacuum in the said mains, keirs, and also in the material or load wound upon the perforated holders 33. I then open valve 25^a connecting manifold 27 with the mains, at the same time opening say valve *a'* communicating by the pipe *c'* with the elevated tank *c*, Fig. 5, containing (for the time being we will suppose) the scouring liquor. The latter now flows from the tank through the open connec-

tions into the bottom chambers 6^e of the keirs, thence upwardly through the series of holders and material mounted thereon into the main chambers of the keirs. When the latter are sufficiently filled the ejector is shut off, also closing the valve 24^c, at the same time opening valves 22^a, 10^a, 9^d, 24^a, 8^d. I then start the pump 7, taking care that the pointer α of the distributor 35 indicates that the flow from the pump is into the bottoms of the keirs, or as represented in Figs. 10 and 12. The result of the pump's action is then to force the liquor into the distributor, then past the valve 9^d downwardly into the mains 9 and T's 13, and from the latter into the bottoms of the keirs, thence upwardly through the holders, &c., into the upper pipes 6^e and mains 14, past the valves 10^a and downwardly through the connection 10^b into the distributor, and from the latter it flows upwardly into pipe 23 to the top of the heater or reservoir 8. As soon as the liquor attains a sufficient height in the heater, or say to the level o , o , Fig. 14, (the glass 8^e Fig. 2 indicating the level) the valve a' connected with the said supply pipe c' is closed and the distributing valve disk 38 set in motion by means of the worm gearing actuated by a link-belt w^4 , see dotted lines Fig. 10; said belt being started by shipping mechanism, &c., in any well-known manner. The now revolving disk and its mechanism in connection with pump 7 and heater act to automatically and intermittently swing or vibrate the wing 36 at certain prearranged intervals, thereby alternately diverting the flow of liquor; one revolution of the disk causing the liquor to flow say into the top of the keirs, the next revolution diverting it into the bottom, and so on alternately as hereinbefore described. When the liquor has thus been sufficiently circulated back and forth through the material or load carried on the holders the distributor 35 and pump 7 are stopped. The scouring liquor is now discharged into the sewer by opening valves 11^a, 21^c and 34; the latter is employed to quickly empty the keirs, the same being operated by the hand-wheels 34^a. If desired, however, the pump may be used to return the liquor to the tank c whence it came. In the latter case instead of opening the series of valves last-named the valve 22^a is first closed thus shutting off the delivery side of the pump from the keirs, the keirs then draining into the mains 9, 24, and 21 by opening the valves 24^c and 34. The valve 25^b is now opened thus establishing a circulation downwardly between the delivery side of the pump and the manifold 27; the valve 25^a being closed to separate the delivery from the suction. If the pump 7 is now started and the valve a' opened the liquor contained in the keirs, heater and piping is returned to the tank c . In like manner liquid may be returned to any other of the tanks shown (h , m or l^2) by simply opening the corresponding valve connecting them with the manifold. All drip

remaining in the mains 24, 21 and manifold is drawn off through the smaller valved pipes 21^c and 27^a. Now supposing all valves previously opened to be closed, I will next describe the manner of rinsing the material just scoured and still mounted within the keirs. The distributor 35 is first set to deliver the flow from the pump into the bottom of the keirs, after which the several valves 22^a, 9^d, 9^a, 24^a, 10^a, 25^a, 15^a, 15^c, 15^d, 8^d are opened, and also the valve a^2 , which latter we will suppose connects the manifold 27 with a tank h (Fig. 5) containing either hot or cold water for rinsing purposes. The water now flows into the mains 21, 24, &c., and as soon as it appears in the glass gage 8^e of the reservoir or heater 8 the main pump is started. The water is thereby drawn through the keirs and material; the air they contain being driven into the air chambers 14^b and escapes therefrom into the sewer through the piping 15, 15^b and interposed open valves. After the keirs are filled with the rinsing fluid and have overflowed sufficiently into the heater 8 as previously described, the valve a^2 is closed, the automatic distributor is put in motion and the operation of forcing the water back and forth through the material is then continued until the material is sufficiently rinsed, when the now charged rinsing water is run off into the sewer by opening the bottom valves 11^a, 21^c and 27^a. The mordanting and subsequent rinsing of the material are effected in the same manner as the scouring and rinsing just described; obviously the only change being made is the opening and closing of the valve a^3 connecting the manifold 27 with the mordanting tank m . Except when using oxidizable dyes, such as indigo, it is not absolutely necessary to create a vacuum in the apparatus before introducing the liquor as the only advantage resulting therefrom is that it insures a more perfect impregnation of the material being treated. The heating or cooling of the treating liquors is effected by coils 41 in the closed heater or reservoir 8 to which either steam or cold water is admitted by opening the valves of the piping 8^a or 8^b, which enter the T 41^b. See Fig. 14, &c. In dyeing the material, if the dye-stuffs to be used are diluted in supply tanks communicating with the manifold 27 and its valves, the manner of procedure in introducing the dyeing liquor is the same as that employed in the operation of scouring and rinsing, but if compound shades are to be dyed or the dye-stuffs to be used are in a dry, pasty or concentrated form, the apparatus is first filled with water as before described in the operation of rinsing and the dye-stuffs selected are dissolved in the tank 30, and water and steam pipes k' , k connected therewith supply the solvent and heat for the first tank full of concentrated dye. When the pump 7 and distributor 35 have been started up and the circulation through the material established the concentrated dye is run from the tank 30

through filter 50 into small pump 29, which latter injects the same into the bottom of the heater 8, via pipe 29^a and valve 29^b, where it is being constantly diluted with the liquor circulating through the apparatus and material. When the tank 30 is partly emptied, a pipe *k*² leading from pump 7 and having a valved connection into said tank is made to supply a small stream of liquor which is kept running until it is assumed that all the dye-stuff in the said tank and filter is dissolved and combined with the circulating liquor. Now supposing that the liquor has been sufficiently heated and circulated, if a sample of the material being dyed is withdrawn from the keir through the testing-valve 31 and it is found to be deficient in any particular dyeing material, or materials, such deficiency is supplied by putting it into the tank 30 and diluting it with liquor furnished from pipe *k*² and is then injected by the pump 29 into heater 8 as previously described, such additions being made from time to time or until the desired shade is obtained. If the dye-stuffs to be added are of such a nature that a cooling of the liquor is desirable before they are introduced into the circulation, the steam is shut off from the heater at 8^a and cold water turned on at 8^b; when the liquor is cool enough, as may be determined by the thermometers 4 secured to the keirs, the new dye is injected, the cold water turned off and steam turned on again.

In using certain dye-stuffs it is desirable to oxidize the liquor while it is in circulation and for this purpose air is forced into the top of the heater through the valved pipe 8^c and the surplus escapes into the atmosphere through the pipe 8^d. The valve 34 (Fig. 9, &c.) is always opened when the keirs are being emptied and always closed when filling or working, or when the blast is on, as hereinafter described. When the treating or dyeing of the material is completed the liquor is returned to its corresponding supply tank, or it may be drained into the sewer; and as soon as it has entirely left the upper chamber of the keirs, the valves 11^a being open and all the other valves closed, the gates or valves 14^a are opened and a current of air under pressure from the blower 28 is conducted into the chambers 14^b communicating directly with the upper portion of the keirs; the action of the air being to drive before it or force out the liquor contained in the material under treatment through the perforations of the holders 33 into the lower chambers 6^c and thence into the sewer. The air thus employed may be ordinary atmospheric air or it can be drawn from a source which heats and dries the air before entering the blower. The blast can be continued until all moisture is carried off or evaporated from the material, thus leaving the latter perfectly dry. I would add that if desired the material may be removed from the keirs

in a semi-dry state and the drying completed in any suitable manner.

It is obvious that both keirs need not be operated at the same time, as each has independent valved connections communicating with the pumps, blower and sewer; therefore the material in one keir can be treated with the several liquids while the material is being loaded, unloaded or dried in the other keir.

In treating materials with indigo, I prefer to prepare or store the cold solutions in a reservoir or tank *i* (Fig. 5) preferably located below the lower inlet 11 to the keir; said tank communicating with valves 12^a, and said inlets by means of the piping 12. A vacuum is created in the entire apparatus by first opening the several valves, which cause the different parts of the apparatus to communicate with each other, while the ejector or exhauster is being worked, and at the same time closing the inlet and outlet valves 8^c 8^d, on top of the heater. When a sufficient vacuum is formed the whole is filled with indigo liquor which is circulated through the material being treated, and said liquor can be enriched with concentrated indigo white solution in the same manner that other treating liquors are enriched and circulated as previously described. When this has been done sufficiently long to enable an even saturation of the material being treated, with the indigo solution, the temperature of the liquid is gradually raised to the desired degree, the circulation and reversing of the flow being kept up until the proper shade is obtained (as may be determined by samples taken through the testing valve 31). The valves 12^a are then re-opened, air at the same time being admitted to the top of the keirs and heater through valves 8^d, 15^a, 15^c, 15^a and piping 15, thereby allowing the indigo liquor to flow back into its reservoir or tank *i*. As soon as the keirs are thus emptied, the valves 12^a are closed and valves 11^a and 14^a opened, followed by admitting air under pressure from blower 28 as before described. The air in passing through the material oxidizes the indigo white fastened to said material into indigo blue or indigotine at the same time driving out any surplus or remaining liquor as before stated. The pressure gages 5^a 5^c, Fig. 1, respectively indicate the pressure in the upper and lower chamber portions of the keir; the difference between the readings of the two pressures indicates to the operator at any time the amount of resistance being used to force the treating liquor through the material. By watching these two gages and the pump-gage *p* the attendant can determine whether the apparatus is working properly or otherwise.

My improved apparatus and system may be adapted to the treatment of textile material by means of the arrangement represented by Figs. 32 to 36, inclusive, without departing from the spirit of the invention. That is to

say, a pair of keirs 1^a are employed, which in practice are both open or both closed. (In the drawings, Fig. 36, one keir is represented as having a closed top the other being open, the cover being indicated by dotted lines.) In this arrangement the keirs are only partially filled with the treating liquids, enough being used, however, to completely submerge the filled holders 33, as clearly shown. These latter are mounted in sockets 32 communicating directly with a bottom chamber 6^c substantially as before described. A valve 34 is used to quickly empty the keirs of liquor into said chamber when desired. This chamber in turn communicates with a series of branch pipes 60 arranged to distribute the liquor over the whole surface of the chamber. These pipes 60 connect with a central cross opening into a vertical T 13 communicating at the bottom with sewer through the pipes 11 and valves 11^a; the lateral branch or nozzle of the T communicates indirectly with the pump 7 by means of the piping 9, valves 9^a, &c., and with the exhauster 28 by the branch or by-pass piping, 57, 57^b, 57^c and valves 57^a, leading from pipe 9. The main 9 is connected directly to the distributer 35 (see Fig. 32), which latter opens into the delivery side of the pump by pipe 22, the pump 30 suction being connected to the main 21 by the rising main 21^a. The main 21 communicates with the manifold 27 by valves 25^a; the manifold in turn being connected with the several supply tanks, as before described, 35 through the pipes c', h', m' and l' and corresponding valves, a', a^b, a^c, a^d.

From the foregoing it will be seen that the pump 7 discharges into the bottom of the keirs, via pipe 22, distributer 25, piping 9, 9^a, 13 40 and 60, and into the upper part of the keirs, upon reversing the valve 35, by piping 10^b, 10 leading from the latter and the interposed valves 10^a, see also Fig. 36. The return flow from the top and bottom of the keirs to the 45 pump is through the lower nozzle of the distributer into the main 21 and thence upwardly therefrom through suction pipe 21^a.

The keirs 1^a are each provided with an 50 ejector, vacuum gage, water-glass and testing valve substantially as before described with reference to the keirs 1. These appliances are not, as a rule, employed except when the covers 62 are used. These covers are provided with an air inlet 8^c, an outlet 8^d 55 and a main connection 61 having a valve 61^a, the latter arranged to receive air under pressure from a blower, or it may be opened to the atmosphere to admit air to be drawn through the keir and material by an exhauster 28, 60 the waste air thus exhausted passing into the atmosphere again via pipe 59. Steam for heating the liquor and concentrated treating materials is introduced from the proper source into the circulation through the small 65 pipe 64 communicating with the T's 13. It will be seen that an air space 63 is formed between the level of the liquor and the top

of the keir; the upper inlets and outlets of the keirs being located above the top of the holders 33.

I will now describe the manner of circulating the liquor through the keirs and material represented by Figs. 32 to 36, assuming that the keirs have been first filled with the holders as hereinbefore described. Upon opening the proper valve at the manifold 27 (corresponding to the treatment desired) communicating with the respective tank or reservoir the liquid immediately fills the manifold and flows into main 21 by opening valve 25^a. The distributer 35 being now set to deliver the flow from pump into the bottom of the keirs the valves 9^a and 10^a are opened and pump 7 started. As a result the liquid is forced from the pump through pipe 22 into the top of the distributer, the valve 36 of the latter diverting the flow into main 9, through valve 9^a, T's 13 and branch pipes 60 into bottom chambers 6^c, thence upwardly through the sockets and holders into the air chamber 63; from the latter it flows outwardly through the valves 10^a, piping 10, 10^b, to the distributer (see Fig. 32) and through it into the main 21 and from thence via connection 21^a to the pump, thus completing the circuit. 95 When the liquor has attained a sufficient height in the keirs the main valve 25^a is closed, at the same time shutting off the tank supply, followed by starting the distributer; the latter in its movement now acts to periodically reverse the direction of circulation as hereinbefore described. In this case, however, the circulation is effected mainly through gravity and suction in connection with the pump. When the treating-liquor has been 105 thus automatically passed back and forth through the material for a sufficient length of time it can be returned to the tank whence it came by stopping the distributer and setting it with the pointer x upward so as to direct the flow from the pump to top of keirs, at the same time closing valves 10^a and opening valve 25^b and the one communicating with the manifold and supply tank. The keirs will then drain to the pump through the piping 9, 21 and interposed distributer; the pump then forces the liquor therefrom through the pipe 22 and distributer into piping 10^b, 25, and valve 25^b to the manifold, and from the latter back to the supply tank. If desired the 110 liquor can be discharged into the sewer through the piping 11 and valves 11^a, communicating with the T's 13. When the liquor has been drawn from the keirs all the valves previously opened are closed and valves 115 57^a and 61^a opened. The exhauster 28 is then started thereby drawing atmospheric air into the keirs and downwardly through the material and holders, the current thus produced carrying with it any liquor left in the material and delivers it into the box 58 from whence it may be drawn by the valve 58^a (Fig. 32), the air passing from the exhauster by pipe 59.

I would state that the material, in the form of twisted or untwisted sliver or yarn, &c., as the case may be, is first wound upon the barrels of the perforated holders 33 in any suitable manner. After the filled perforated holders have been removed from the keir, following the treating operation, the load or material thus treated is next unwound therefrom and subsequently subjected to the usual operations of drawing, spinning, &c.

While admitting that it is not broadly new to treat fibrous materials contained on perforated holders mounted in keirs through which the treating-liquor circulates, as stated in the beginning of this specification, yet so far as I am aware my improved apparatus and system illustrated and described herewith and as embodied in the appended claims are new and novel.

20 For certain treatments it is not necessary to use the reverse current in circulating the treating-liquid; therefore it can be passed through the material in one direction during the whole operation; as for example, when the 25 materials are being scoured, mordanted or bleached. In such case the valve 36 is first set to divert the liquid in the desired direction, the valve-driving mechanism meanwhile being idle.

30 I claim as new and desire to secure by United States Letters Patent—

1. In an apparatus for treating textile materials, a treating keir, a pump, connecting with the inlet and outlet chambers of said keir through a mechanically operated four-way valve, and piping through which the said pump discharges alternately into said inlet and outlet chambers through the four-way valve under pressure and through which said 35 pump at the same time alternately exhausts or sucks through the four-way valve from said chambers, substantially as described.

2. In combination, a keir, a pump and a system of circulating pipes which include the 45 keir and pump, a distributer having its valve chamber with passages opposite each other, leading to opposite ends of the keir, and passages also opposite each other leading to opposite sides of the pump, and a winged valve 50 in said distributer, substantially as described.

3. In an apparatus for treating textile fibers, and in combination, a keir, a reservoir and a pump, all included in a system of valved pipes, said reservoir being arranged to maintain a head on the pump and on the material in the keir and communicating with the pump suction and in reversible communication with opposite ends of the keir through a four-way distributer also in said system, and 55 mechanism for operating said distributer, said pipes and distributer being arranged to reverse the current through the keir, substantially as described.

4. In an apparatus for treating textile fibers, 60 and in combination a closed keir, a closed reservoir, and a pump, all included in a sys-

tem of valved pipes, said reservoir communicating with the pump suction and opposite ends of the keir through a four way distributer, also in said system, and mechanism for 70 operating said distributer, said pipes and distributer being arranged to reverse the current through the said keir, substantially as described.

5. In an apparatus for treating textile fibers, 75 and in combination, a closed keir, and a closed reservoir arranged on a higher plane than said keir, a pump, connecting with the reservoir's outlet a system of valved pipes, leading through the keir and a distributer connecting with the reservoir's inlet arranged to reverse the circulation through said keir, and valved pipes leading also from said distributer arranged to maintain the circulation downward through said reservoir, substantially as described.

6. In an apparatus for treating textile materials mounted on perforated holders communicating with the inlet and outlet chambers of the treating keir, a suitably connected mechanically operating four way valve or distributer located below the keir arranged to automatically reverse the direction of the treating liquid while the latter is passing through said material, and a force pump discharging the treating-liquid into said keir chambers alternately upon reversing the distributer, provided with pipes whereby the return flow from the chambers is made by gravity, or gravity and suction through the 100 bottom of the distributer and thence into the suction side of the pump, substantially as described.

7. In an apparatus for treating fibrous materials by circulating the treating-liquid to 105 and fro through the material in opposite directions at predetermined intervals of time, a heater located in the piping system arranged to receive said liquid as it is discharged from the keir, a pump for effecting the circulation taking its supply from the heater, and an intermittently operating distributer or four way valve for alternately reversing the flow of the 110 circulating liquid from the top to the bottom of the keir, and communicating with the inlet 115 to the heater substantially as described.

8. In an apparatus for treating textile materials, provided with a treating keir, a heater or reservoir and a liquor circulating pump, the combination therewith of an intermittently operating four way valve having the top nozzle communicating with the top of the heater, the bottom nozzle with the bottom of the heater, via the pump, and the two lateral nozzles with the top and bottom of the keir, 125 substantially as described.

9. In an apparatus for treating textile fibers, and in combination, a keir, a pump, a reservoir having in it a coil for changing the temperature, and a system of valved pipes including said keir, reservoir and pump, and a four way distributer in said system, connec-

tions through said keir, combined with reversing mechanism and connections through said reservoir, all substantially as described.

10. In an apparatus for treating textile fibers, and in combination, a keir, a reservoir and a pump, a distributor connected to the force and exhaust sides of said pump, pipes leading from the distributor through the keir, and a discharge pipe leading from the distributor to the said reservoir, said discharge pipe being higher than the keir, and a pipe leading from the reservoir to the distributor, all substantially as described.

11. In an apparatus for treating textile materials, a piped keir containing perforated holders carrying said material a pump for circulating the treating-liquid, and a heater or reservoir, in combination with an intermittently operated four way valve or distributor having four nozzles, one communicating with the inlet chamber of said keir, one with the outlet chamber, one with the discharge of said pump, and one with the suction side of the pump through the said heater, the latter being located above said suction, and maintaining a head on the pump, substantially as described.

12. In an apparatus for treating textile fibers, and in combination, a closed keir, a closed reservoir, having in it a coil for changing the temperature, and a system of valved pipes including said keir, reservoir and pump, and a four way distributor in said system, with connections through said keir, arranged for reversed currents and connections through said reservoir, the whole forming a closed system, substantially as described.

13. In an apparatus for treating textile materials, the combination with the treating-keir, the valve and pipe connections, forming a closed system, and a circulating pump, &c., arranged to circulate the treating-liquids throughout the system of coils located in the system and arranged for cooling and heating the treating-liquid, as desired, during its passage or circulation, substantially as described.

14. In combination with a keir, and pump, and a system of valved pipes whereby circulation is maintained through the keir, a heater or reservoir connected with said system of valved pipes, said heater or reservoir having interior coils connected with valved steam and water pipes, whereby it may be used either as a heater, cooler, or reservoir, substantially as described.

15. In combination with a keir and pump, and a system of valved pipes, whereby circulation is maintained through the keir, a heater or reservoir connected with said system of valved pipes, said heater or reservoir having interior coils connected with valved steam and water pipes and having also a pipe connected with a blower, all substantially as described.

16. In an apparatus for treating textile materials, and in combination with a pump or keir a heater or reservoir adapted interiorly

for the circulation of treating-liquid and provided with coils for the circulation of cooling and heating mediums for the purpose of changing the temperature of the treating-liquid, said coils being connected with valved pipes supplying said mediums substantially as described.

17. A sampling valve, consisting of a body 75 portion, having a seat for the valve, a hole in said seat communicating with the interior of the keir, a valve having a facing fitted to hold the thread without cutting it, means for forcing the valve to its seat and means for releasing said valve, substantially as described.

18. In an apparatus for treating textile materials, the combination with a closed treating-keir, of a testing-valve secured thereto, consisting of a head having a valved opening 85 communicating with the keir's interior and adapted for the passage of an end of the material under treatment, a self-closing valve for closing said opening, and a movable sleeve fitting the exterior of the head portion, substantially as described.

19. In an apparatus for treating textile materials mounted in a closed keir, the self closing testing valve having the tubular aperture or perforation connecting with the keir's interior for the passage of the end of the material under treatment, substantially as described.

20. In an apparatus for treating textile materials, the combination with a closed treating-keir and one or more spools or holders mounted therein carrying said material while under treatment, of a self-closing testing-valve 100 communicating with the keir's interior and adapted for the passage through it of an end 105 of the material under treatment, and an interior hood or shield through which said end passes from the spool to the valve, substantially as described.

21. In an apparatus for treating textile materials, the combination with a closed treating-keir, of a self-closing testing-valve secured thereto and communicating with the keir's interior, said valve being adapted for the passage of an end of the material under treatment, the valve and its seat, one or both, having a yielding face to preserve the integrity 115 of the sample end when the valve is seated.

22. In an apparatus for treating textile materials, provided with a keir having inlet and outlet chambers and perforated holders mounted in the keir communicating with said chambers, the combination therewith of a supplemental perforated holder communicating with one of the main holders, a testing-valve 120 communicating with the interior of the keir having an opening through it for the passage 125 of a yarn or thread and mechanism for circulating the treating liquid through the materials, substantially as described.

23. In an apparatus for treating textile materials, a suitably connected keir having a bottom chamber separated from the main chamber by an apertured partition and hav-

ing a series of holders fitting said apertures, each holder consisting of a capped central perforated tube, a perforated barrel onto which the material to be treated is wound, 5 and closed ends or heads, whereby when in use the treating-liquid passes from the said bottom chamber upwardly into the interior of the holder and outwardly therefrom through the load of material, and vice versa, substantially as described.

24. In an apparatus for treating textile materials, a keir having a top head provided with a central opening from which extend radiating pipes having smaller openings communicating with the interior of the keir, and a similarly constructed bottom head having in addition an interposed or supplemental chamber communicating with the interior of the keir by a series of sockets, arranged to 20 receive perforated holders, substantially as described.

25. In an apparatus for treating textile materials with circulating liquids, a four way valve distributor arranged to reverse the direction of the treating-liquid, a continuously revolving disk-wheel provided with a toothed segment, a pinion arranged to inter-gear therewith to actuate the valve proper, and a locking plate adapted in use to engage the 30 disk-wheel to prevent movement of the valve after the pinion and segment have ceased to act, substantially as described.

26. In an apparatus for treating textile materials, with circulating liquids provided with 35 a mounted four way valve or distributor arranged to reverse the flow of said liquid, mechanism for automatically operating said valve consisting of a loosely mounted disk adapted to continuous rotation, a pointer-carrying plate intermittently rotated by said disk, an arm or crank secured to the stem of the valve proper and a link jointed to the crank and plate, whereby the valve is vibrated to and fro in unison with the intermittently 40 rotated plate, substantially as described.

27. In combination with a keir and pump, and a system of valved pipes, whereby circulation is maintained through the keir, a heater or reservoir connected with said system of 50 valved pipes, said heater or reservoir having interior coils connected with valved steam or water pipes, and having also an air pipe connected with a blower, and a pipe connected with a concentrated liquor supply, substantially as described.

28. In an apparatus for treating fibrous materials, a tank for containing concentrated dye-liquor, a filter communicating therewith, a pump for forcing the liquor from said tank 60 and filter into the main circulation or treating-liquid, and mechanism for circulating the latter through the holders and material, substantially as described.

29. In an apparatus for treating fibrous materials mounted on perforated holders communicating with the inlet and outlet chambers of the treating-keir, the combination there-

with of a dye-tank provided with a strainer and collecting chamber, a filter connected with the tank having a bed of filtering material, a 70 strainer and collecting chamber, means for forcing liquor from said tank and filter into the main circulating system, and mechanism for repeatedly circulating the treating liquid through the fibrous material, substantially as 75 described.

30. The system for treating fibrous materials, substantially as hereinbefore described, the same comprising the following instrumentalities, viz., one or more keirs having a 80 series of perforated holders mounted therein carrying the material under treatment, a heater or reservoir into which the treating liquor is discharged from the keirs, a series of supply tanks, a dye-liquor tank and filter communicating with each other, a pump arranged to discharge the dye-liquor into said heater or circulation, an automatically operating four way valve or distributor arranged to reverse the flow of the treating-liquor at predetermined intervals of time, a main pump for effecting the circulation of the treating-liquor, 85 and valved connections communicating with the several parts, for the purpose specified.

31. The system for treating fibrous materials, substantially as hereinbefore described, the same comprising the following instrumentalities, viz., one or more keirs having a 90 series of perforated holders mounted therein, carrying the material under treatment, a 100 heater or reservoir into which the treating-liquor is discharged from the keirs, a series of supply tanks, a dye-liquor tank and filter communicating with each other, a pump arranged to discharge the dye-liquor into said heater 105 or circulation, an automatically operating four way valve or distributor arranged to reverse the flow of the treating-liquor at predetermined intervals of time, a main pump for effecting the circulation of the treating-liquor, 110 a blower arranged to circulate air through the materials under treatment, and valved connections communicating with the several parts, for the purpose specified.

32. The system for treating fibrous materials, substantially as hereinbefore described, the same comprising the following instrumentalities, viz., one or more keirs having a 115 series of perforated holders mounted therein carrying the material under treatment, an 120 ejector, or other suitable means for forming a vacuum in the keirs, a heater or reservoir into which the treating-liquor is discharged from the keirs, a series of supply-tanks, a dye-liquor tank and filter communicating with 125 each other, a pump arranged to discharge the dye-liquor into said heater, an automatically operating four way valve or distributor arranged to reverse the flow of the treating-liquor at predetermined intervals of time, a 130 main pump for effecting the circulation of the treating-liquor, and valved connections communicating with the several parts, for the purpose specified.

33. The system for treating fibrous materials, substantially as hereinbefore described, the same comprising the following instrumentalities, viz., one or more keirs having a series of perforated holders mounted therein carrying the material under treatment, an ejector or other suitable means for forming a vacuum in the keirs, a heater or reservoir into which the treating-liquor is discharged from the keirs, a series of supply tanks, a dye-liquor tank and filter communicating with each other, a pump arranged to discharge the dye-liquor into said heater, an automatically operating four way valve or distributor arranged to reverse the flow of the treating-liquor at predetermined intervals of time, a main pump for effecting the circulation of the treating-liquor, a blower arranged to circulate air through the materials under treatment, an indigo tank communicating with the lower discharge outlet of the keirs by an independent valved connection and valved piping connecting the keirs with the several parts, for the purpose specified.

34. In an apparatus for treating textile materials, having a closed system of circulation the combination of a dye-tank, a filter in connection with a suitable supply therefor and a pump or other injecting mechanism arranged to discharge dye-liquor from said tank and filter into and be diluted with the circulating treating-liquor, substantially as described.

35. In an apparatus for treating textile materials mounted on perforated holders communicating with the inlet and outlet chambers of the treating-keir, the combination therewith of a mechanically operating piped distributor located below the keir arranged to intermittently reverse the flow of the treating-liquid, a pump also located below the keir connected with said distributor and keir-chambers, a valved manifold communicating with one or more supply tanks, distributor and pump, and mechanism for circulating air through the material under treatment, substantially as described.

36. An apparatus for treating fibrous or textile materials, the same comprising a plurality of keirs arranged to contain such material while under treatment, one or more supply tanks, a circulating pump, means for changing the temperature of the circulating treating-liquor, mechanism for forcing air and creating a vacuum, an intermittently operating distributor, and valved piping connecting the several parts, all combined and adapted for operation whereby at the same time that the material in one keir is being subjected to the treating operation the previously treated material is being dried or removed from the other keir, followed by recharging the latter with untreated material, substantially as described.

37. In an apparatus for treating textile materials, having a force pump therein and system of pipes for the circulation of the treating liquid means for mechanically returning the treating-liquids from the keirs into the reservoirs or supply tanks, the same consisting of a pump, a suction main communicating with the keirs, &c., a stop-valve closing the circulation to the keirs, a valved manifold communicating with the tanks, a valved connection communicating with the pump discharge and said manifold and a stop-valve interposed between the manifold and the pump suction, substantially as described.

38. In an apparatus for treating textile fibers, a closed keir, a closed heater, and a pump, both included in a system of circulating pipes, an indigo tank in communication with said system, and means for introducing the indigo solution from the indigo-tank into said system, substantially as described.

In testimony whereof I have affixed my signature in presence of two witnesses.

EMILE MAERTENS.
